UNITED STATES PATENT OFFICE

JAMES C. MOCK, OF DETROIT, MICHIGAN

HIGHWAY CROSSING SIGNAL

Application filed February 26, 1930. Serial No. 431,616.

This invention relates in general to highway crossing signals for use where highways cross railway tracks, and has more particular reference to a novel form of signal together with control circuits therefor.

The present invention relates to an improvement over that shown in my pending application Serial Number 344,964 filed March 7, 1929.

10 In highway crossing signals it is of the utmost importance not only to indicate to those using the highway a dangerous condition, but also to indicate what these conditions are. It is clear that a mere flashing 15 light signal, for example, fails to indicate from what direction a train is approaching the crossing, and whether or not there may be two trains simultaneously approaching from different directions. As a result of 20 insufficient information with regard to the character of danger existing, accidents may occur.

With the above and other considerations in mind, it is proposed, in accordance with 25 the present invention, to provide a highway crossing signal which not only will indicate when dangerous conditions exist, but also will indicate exactly what these conditions are.

30 More specifically, it is proposed to provide a signal which pictorially represents the actual danger condition existing at the particular moment, and which more certainly arrests attention by having various portions 35 of the picture lighted up steadily, while others are intermittently flashed.

Further objects, purposes and characteristic features of the present invention will appear as the description progresses, reference being made to the accompanying drawings showing, solely by way of example, and in no manner whatsoever in a limiting sense, two forms which the invention can assume.

45 In the drawings:—

Fig. 1 is a wholly diagrammatic view of one form of the invention.

Fig. 2 is a wholly diagrammatic view of a second form of the invention.

50 Referring to the drawings, and first to

Fig. 1, there is here shown a double track line comprised of track rails 1, across which runs a highway 2, there being detector track circuits defined by insulated joints 3, each circuit having a usual battery 4 connected across the rails at one end of the circuit and a track relay 5 or 6 connected across the rails at the other end of the circuit.

Positioned at the right side of the highway, at each side of the railway tracks, are signals *Sig* and *Sig*¹, for warning those using the highway of dangerous conditions at the crossing.

The two signals referred to are identical in arrangement and control, and accordingly it is unnecessary to specifically describe more than one of the signals, all remarks applying to one signal likewise applying with equal force to the other signal.

The signal *Sig* is of a suitable size to readily be seen and includes at its top the usual legend "Railroad crossing" in letters painted on a background of any desirable sort. Below the "Railroad crossing," and formed preferably of neon or other gas tubes so as to give an attention arresting illuminated sign when energized, is the word "Train." Below the word "Train," are two pictorial representations *Te* and *Tw* of a moving train, facing in opposite directions, and each including a headlight *Le* and *Lw* and a representation of smoke *Se* and *Sw*, all of these parts being preferably formed, as described in connection with the word "Train," of gas tubes for giving an arresting illumination when energized.

Included in the system, as shown in Fig. 1, are two sets of cross connected flashing relays, one set comprising relays 7 and 8, and the other comprising relays 9 and 10; in each set one relay being connected to have an energizing circuit running through a front point of the other, with the other connected to have an energizing circuit including a back point of the one, whereby, on energization, these relays alternately intermittently pick up and release.

The system shown in Fig. 1, and described above, operates in the following manner.

Assuming an east bound train to be approaching the highway 2, on entering the track section of relay 5, this relay is shunted out to release its contact finger 11 to thereby place energy on the flashing relays 7 and 8 through wire 11¹, and also through wire 12, through the pictorial train T_e to thereby energize T_e and pictorially show on signal Sig a picture of a train outlined by illuminated tubes, with the pictorial representation of the train pointing in the same direction as the actual train which is approaching the crossing.

As soon as energy is placed on the flashing relays 7 and 8, relay 8 first picks up through a circuit including contact finger 14 and back point of relay 7 to thereby complete the energizing circuit for relay 7 through a circuit including contact finger 11 and back point of relay 5 and contact finger 13 and front point of relay 8. Shortly after relay 8 picks up, relay 7 picks up to break the energizing circuit for relay 8 at contact finger 14 and back point of relay 7, whereby the cycle is repeated so long as relay 5 remains down. Thus, with the flashing relays 7 and 8 energized, contact fingers 15 and 16 of relay 7 intermittently pick up and release, contact finger 15 thereby intermittently energizing and de-energizing the word "Train" of signal Sig through a circuit including contact finger 15 and front point of relay 7.

Contact finger 16 of relay 7 when picked up energizes in multiple, the smoke S_e and the headlight L_e of the pictorially represented east bound train T_e , through a circuit including contact finger 16 and front point of relay 7.

The various parts of signal Sig are connected in multiple with the corresponding parts of signal Sig^1 whereby in signal Sig^1 the east bound train T_e^1 together with its smoke and headlight S_e^1 and L_e^1 , and the word "Train" are likewise illuminated.

It will be observed from the above that the energization of the word "Train" is intermittent, to give a flashing effect, and likewise is the pictorial representation of the smoke and of the headlight, while the energization of the train T_e is steady, rather than flashing. It is also to be noted that west bound train T_w together with its smoke S_w and headlight L_w is not illuminated by an east bound train on the east bound track.

In the case of a west bound train approaching the crossing, and shunting out relay 6, a similar operation to what has just been described takes place except for the fact that the pictorial representation of the west bound train T_w is illuminated, to thereby faithfully and accurately represent, not only the dangerous condition, but exactly what constitutes the danger. The word "Train" is, however, illuminated in this case

also, through a circuit including contact finger 17 and front point of relay 10.

From the above it can be seen that each of the two signals Sig and Sig^1 , on the approach of an east bound train, shows the outline in steady illumination of an east bound train together with the word "Train" and the smoke and headlight of the east bound train, illuminated through an intermittently interrupted circuit, to thereby give a flashing illumination, whereby to more certainly attract the attention of one approaching the crossing.

In the case of a west bound train the same illumination occurs with regard to the word "Train" together with the corresponding illumination of the pictorially represented west bound train, together with its smoke and headlight.

If there be simultaneous approach to the crossing of both an east bound and a west bound train, then the entire signal is illuminated.

With the above type of signal and control means, it is quite out of the question for one approaching the crossing, to wait until an east bound train has cleared the crossing and then deliberately cross over to be struck by a west bound train at the crossing, in the manner which might occur with the present highway crossing signals.

In Fig. 2 is shown a slightly modified form of the invention wherein a single set of flashing relays is employed, and is represented diagrammatically by the enclosed square 100 entitled "Flasher." In this form, the single flasher is energized when either of the track circuit relays 18 or 19 is shunted out by the presence of a train approaching the crossing, whereby in either case the single flasher is energized to place intermittently interrupted energy on the word "Train" of the signals, through contact finger 20 and front point of the flasher. Likewise the outline of the train corresponding to the actual approach train is steadily illuminated through a circuit, in the case of an east bound train, which includes contact finger 21 and back point of relay 18, and wires 24, 25 and 26.

The smoke and headlight of the illuminated train, assuming for example the approach of an east bound train, is energized intermittently through a circuit including contact finger 22 and front point of the flasher, and contact finger 23 and back point of relay 18.

In the form of invention shown in Fig. 2, one of the sets of flashing relays employed in the form of Fig. 1, is eliminated, while an additional contact finger is added to each of the track circuit relays 18 and 19.

In each form of the invention described, therefore, an accurate pictorial representation, in an arrestingly illuminated form, of

the actual danger conditions existing, is displayed to one on the highway 2, when approaching the railroad tracks from either side.

5 In summary, it is thus seen that the word "Train" is steadily illuminated, dependent on the approach but regardless of the direction of approach of a train, the pictorial representation of one or the other of the 10 trains T_e or T_w is steadily illuminated depending on the direction of approach of a train to the crossing, while the smoke and the headlight of the steadily illuminated train is intermittently illuminated to give 15 a flashing effect.

The above rather specific description of two forms of the present invention is given solely by way of illustration, and is not intended, in any manner whatsoever, in a limiting sense. Obviously, the invention can assume many different physical forms, and is susceptible of numerous modifications, and all such forms and modifications are intended to be included in this application, as 20 come within the scope of the appended claims.

Having described my invention, I now claim:-

1. In a signalling system for highway 30 crossings where a highway crosses a railroad track, a signal including illuminable pictorial representations of trains facing in opposite directions, circuits for selectively illuminating said representations, and control means for said circuits, automatically responsive to traffic conditions, to illuminate that representation corresponding to actual 35 approaching danger.

2. In a signalling system for highway 40 crossings where a highway crosses a railroad track, a signal including illuminable pictorial representations of trains facing in opposite directions, each representation of a train including illuminable smoke and head 45 light, circuits for selectively illuminating said representations and including intermittent interrupting means in certain of said circuits, and control means for said circuits automatically responsive to traffic conditions 50 to illuminate that train representation corresponding to actual approaching danger.

3. In combination, a stretch of track crossed by a highway, a crossing signal at the intersection and including pictorial illuminable representations of two trains facing in opposite directions and parallel to the track, and means, on approach of a train on said track to said highway, to illuminate only that representation corresponding in direction to that of the approaching train.

4. In combination, a stretch of track crossed by a highway, a crossing signal at the intersection and including pictorial illuminable representations of two trains facing in opposite directions and parallel to the

track, each representation including an outline of a train, and a head light on the train, separate circuits for energizing the train outline and the headlight, intermittent interrupting means in one of said circuits for causing a flashing energization of the current, and means on approach of a train on said track to said highway, to energize said separate circuits so as to illuminate only that train representation corresponding in direction to that of the approaching train. 70

5. In combination with a highway crossing, a railroad track, a highway crossing signal having a background, the word "Train" in illuminable characters on the background and the illuminable pictorial representation of two trains, facing each other thereon, and each having a headlight, and smoke issuing therefrom. 80

6. In combination with a highway crossing, a railroad track, a highway crossing signal having a background, the word "Train" in illuminable characters on the background, the illuminable pictorial representation of two trains, facing each other 90 on the background and each having a headlight, and smoke issuing therefrom, an energizing circuit for the word "Train", an energizing circuit for each train representation, and an energizing circuit for each set 95 of headlight and smoke associated with each representation.

7. In combination with a highway crossing, a railroad track, a highway crossing signal having a background, the word "Train" in illuminable characters on the background, the illuminable pictorial representation of two trains on the background, facing each other, and each having a headlight, and smoke issuing therefrom, an energizing circuit for the word "Train", an energizing circuit for each train representation, and an energizing circuit for each set of headlight and smoke associated with each representation, and interrupting means in 100 the "Train" circuit and the smoke and headlight circuit. 105

8. In combination with a highway crossing, a railroad track, a highway crossing signal having a background, the word "Train" in the illuminable characters on the background, the illuminable pictorial representation of two trains on the background, facing each other, and each having a headlight, and smoke issuing therefrom, an energizing circuit for the word "Train", an energizing circuit for each train representation, an energizing circuit, for each set of headlight and smoke associated with each 110 representation, and interrupting means in the "Train" circuits and the smoke and headlight circuits. 115

"Train" in the illuminable characters on the background, the illuminable pictorial representation of two trains on the background, facing each other, and each having a headlight, and smoke issuing therefrom, an energizing circuit for the word "Train", an energizing circuit for each train representation, an energizing circuit, for each set of headlight and smoke associated with each 120 representation, interrupting means in the "Train" circuits and the smoke and headlight circuits, and automatic control means for selectively energizing said circuits to illuminate "Train" when a train approaches 125

130

the crossing regardless of the direction of approach of the train, and for illuminating only that pictorial representation of a train that corresponds in direction to that of the actual train approaching the crossing.

5 In testimony whereof I affix my signature.
